DESIGN FOR A COMBINED PICTURE AND PHOTOGRAPH FRAME

Benedict Mahon, Stirling, N. J.

Application December 9, 1942, Serial No. 108,982

Term of patent 3½ years

To all whom it may concern:

Be it known that I, Benedict Mahon, also known as Father Benedict, a citizen of the United States, residing in the city of Stirling, county of Morris, and State of New Jersey, have invented a new, original, and ornamental Design for a Combined Picture and Photograph Frame, of which the following is a specification, reference being had to the accompanying drawing, forming a part thereof.

Figure 1 is a front view of a combined picture and photograph frame, showing my design.

Figure 2 is a section along the line 2—2 of Figure 1.

I claim:

The ornamental design for a combined picture and photograph frame, as shown.

BENEDICT MAHON.
